DESIGN FOR AN ELECTRIC IRON

Francesco Collura, New York, N. Y.

Application December 7, 1945, Serial No. 124,474

Term of patent 14 years

(Cl. D49—6)

To all whom it may concern:

Be it known that Francesco Collura, a citizen of the United States and resident of New York, in the county of New York and State of New York, has invented a certain new, original, and ornamental Design for an Electric Iron, of which the following is a specification, reference being had to the accompanying drawing forming a part thereof.

Figure 1 is a side elevation of the electric iron showing my new design;

Fig. 2 is a top plan view; and

Figs. 3 and 4 are front and rear elevations respectively of the same.

I claim:

The ornamental design for an electric iron, as shown,

FRANCESCO COLLURA.
